BEADED ROSETTE

Julia Engelmeier, Pittsburgh, Pa.

Application September 14, 1953, Serial No. 26,785

Term of patent 14 years

(Cl. D3—32)

Fig. 1

Fig. 3

To all whom it may concern:

Be it known that I, Julia Engelmeier, a citizen of the United States, residing at Pittsburgh 13, Pennsylvania, have invented a new, original, and ornamental Design for Beaded Rosettes, of which the following is a specification, reference being had to the accompanying drawing, forming part thereof.

I claim:

The ornamental design for a beaded rosette, as shown.
